DESIGN.

C. BOOZE.
WALL PAPER.

Patented Oct. 21, 1890.

No. 20,228.

UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 20,228, dated October 21, 1890.

Application filed September 27, 1890. Serial No. 366,393. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying photograph, forming part thereof.

10 The leading feature of my design consists of a series of scrolls of the romanesque style arranged in circular form with the circular lines interlacing and forming connected circles, the spaces between the connected circles 15 forming oblong panels, in which are arranged interlacing rosettes of oblong form, as represented in the accompanying photograph. The scrolls occupy the entire space inclosed by the circles. The scrolls and rosette ornaments are printed in any desired color upon tinted 20 paper of any desired color.

What I claim is—

The design for wall-paper herein shown and described.

Witness my hand this 13th day of September, 1890.

CHARLES BOOZE.
